UNITED STATES PATENT OFFICE.

GEORGE AMBORN, OF NEW YORK, N. Y., ASSIGNOR TO J. H. WILLIAMS & CO., OF BROOKLYN,
NEW YORK, A CORPORATION OF NEW YORK.

CHAIN PIPE-WRENCH.

No. 892,111.

Specification of Letters Patent.

Patented June 30, 1908.

Application filed March 8, 1907. Serial No. 361,288.

To all whom it may concern:

Be it known that I, GEORGE AMBORN, a citizen of the United States, residing in the borough of Brooklyn, county of Kings, city 5 and State of New York, have invented certain new and useful Improvements in Chain Pipe-Wrenches, of which the following is a specification.

This invention relates to chain wrenches 10 and similar devices and aims to provide certain improvements therein.

The invention is particularly directed to that type of chain wrenches in which two laterally separated jaws are provided, between 15 which the chain is centrally pivoted so that either side of the wrench may be used. In this type of wrench two locking devices are generally used, which are usually constructed to engage locking pintles formed 20 upon or carried by the chain. In the intended or normal manner of using such wrenches the chain is locked upon the side of the wrench which is opposite the pipe. Occasionally, however, the chain is locked upon 25 the same side as the pipe. This changes the direction of strain materially so that the chain is very apt to slip out of engagement with the lock. This is especially true when the chain is slackened during the return 30 stroke of the wrench for the purpose of obtaining a fresh grip upon the pipe.

According to the present invention I provide a lock which is adapted to securely hold the chain under all of the varying conditions 35 of use, and which at the same time is adapted to be easily engaged by the chain and disengaged therefrom when desired.

Referring to the drawings illustrating my invention, Figure 1 is a side elevation of a 40 chain pipe wrench showing the wrench in the position as normally used; Fig. 2 is a view similar to Fig. 1 showing the wrench with its chain locked upon the same side as the pipe; Fig. 3 is an elevation of the inner face of one 45 of the jaws removed; Fig. 4 is a plan view of the wrench partly in longitudinal section.

In the drawings A designates the shaft or handle of the wrench which has riveted to its forward end a pair of jaws B, B' which are 50 separated laterally a sufficient distance to permit the chain C to be pivoted between them. In this form of wrench the jaws are usually provided with two working faces D, D' so that the wrench may be reversed and 55 one or the other of such faces brought into

operation. Usually two locks for the chain are provided, one on each side of the wrench, in the normal or intended manner of use the chain being engaged with the lock which is upon the opposite side to the pipe. 60

The principal feature of the present invention is the provision of a lock which is adapted to hold the chain during all of the positions which the wrench assumes in use, and which is at the same time capable of being 65 easily engaged and disengaged by the chain.

According to the preferred form of my invention, the chain is formed with a series of locking pintles E which are adapted to engage a locking device or devices formed upon 70 the handle or jaws. Such locking devices are preferably made as illustrated at F in Fig. 3, and comprise hook-like members which are adapted to be connected to the chain by a rearward and outward movement 75 of the latter. As shown, such members are formed on the inner sides of the jaws B, B', although they may be formed upon the handle or other part of the wrench. Each of the locks F is formed with a portion a which projects inwardly a sufficient distance to securely hold the chain when the latter is placed under a longitudinal forward stress as indicated in Fig. 1, which illustrates the ordinary method of using the wrench. The rear portion b of the lock is preferably extended inwardly to the plane of the handle as shown 80 in Fig. 3. Such portion may, however, be constructed in any manner which will prevent the rearward escape of the pintle. 85

In order to permit the insertion of the pintle into the recess of the hook, it is desirable to provide a recess c in the handle in front of and inwardly of the lock which is adapted to receive the end of the link, so that 95 the pintle may pass beneath the forward ends of the locks. To prevent the link which is engaged from dropping inwardly when the wrench is in the position shown in Fig. 1, the portions a of the locks are preferably extended 100 rearwardly to a slight degree. Beyond the recess c in a forward direction the handle retains its full thickness, so that the chain tends to maintain the position shown in Fig. 1, the link which carries the pintle engaged by the lock lying in a direction approximately paralleling the handle. The chain in front of the handle tends to maintain the pintle in engagement with the lock; this effect is obtained to a much greater degree 110

when the chain is placed under a forward longitudinal stress in use. In locking the chain one of its pintles is moved rearwardly beneath the lock, and then outwardly into engagement therewith.

In the use of a chain wrench, the wrench is applied to the pipe or other object in many different positions. Occasionally it is used with the chain locked upon the same side of the wrench as the pipe. This manner of use is illustrated in Fig. 2. In this position the direction of the chain is changed materially from the direction indicated in Fig. 1. The lock, however, is so constructed that it positively engages the locking pindle of the chain in this position. The wrench is also frequently used in a vertical position either with its jaws extended upwardly or downwardly. In none of these positions is there a tendency to unlock the chain either on the forward turn of the wrench or on the return movement to regrip the pipe. This is true whether the chain is locked upon the same side as the pipe, or on the opposite side. It will furthermore be observed that there is no tendency for the weight of the free end of the chain to unlock the latter when the chain is slackened for any purpose. This tendency had been one of the chief defects of several of the well known wrenches now in use, and has constituted a source of danger especially in overhead work on scaffolds or the like. In constructing wrenches of this class it has heretofore been found desirable to extend the handle to a point beyond the central pivot of the chain in order to obtain a secure connection between the jaws and handle. This has required that the handle be formed with a long slot to receive the first link of the chain. This construction has involved the use of deep grooves in the jaws, in order to permit the use of sufficiently thick metal in the handle on each side of its slot.

According to my present invention I form the jaws with thickened rear portions in which the grooves are formed either wholly or partially by a suitable shaping or grooving tool, the groove being so shallow that it extends no further into the metal than the general plane of the inner side of the jaw. This construction is best seen in Fig. 4. By this means the tool can be passed completely across the jaw, moving out of the groove at the end of the thickened portion, and passing idly across the remainder of the jaw. In its complete form the jaw is in effect provided with two ribs d , d' , forming between them the groove f , the bottom of which preferably lies in the plane of the inner side of the jaw as shown. This construction also enables me to connect the parts by the use of a single rivet g , a desirable feature not heretofore attained.

In order to obtain as long a connection as possible between the handle and the jaws

without increasing the length of the latter, I prefer to form the pivot or pin h with a forwardly projecting eye j which corresponds to the first link of the chain as heretofore used. The eye j is formed on one side only of the pivot, so that the handle may be brought close to the pivot as shown in Fig. 4. This feature of my invention provides an extremely strong and simple connection between the handle and jaws, and materially cheapens the construction of the wrench. By fitting the pivot h in sockets as shown in Fig. 4, a further gain in economy is produced, since the pivot maintains its position without the necessity of an additional bolt such as is now used.

It will be understood while I have illustrated my invention as applied to a double jawed wrench having a centrally pivoted chain, that it is applicable to other constructions of chain wrench, and also to other devices of similar character. It will be also understood that instead of providing the chain with locking pintles and the jaws with locking members, this construction may be reversed or otherwise suitably modified while still retaining the advantages of this feature of my invention. Other changes may also be made in the construction herein described without departing from the invention.

What I claim is:—

1. In a chain wrench, the combination of a jaw, a chain, and a locking means for said chain, said means comprising engaging members on the chain and wrench adapted to be connected by a rearward and outward movement of the chain.

2. In a chain wrench, the combination of a jaw, a chain and a lock for said chain, said lock comprising a hook-like member connected with the jaw, said member opening inwardly and forwardly and adapted to engage a part of the chain.

3. In a chain wrench, the combination of a jaw, a chain having locking pintles, and a lock for said chain adapted to engage such pintles, said lock comprising a forwardly turned hook-like member the front end of which is turned inwardly sufficiently to prevent disengagement of the chain when the latter is placed under a longitudinal forward stress in use.

4. In a chain wrench, the combination of a jaw, a chain having locking pintles, and a lock for said chain adapted to engage such pintles, said lock comprising a forwardly turned hook-like member the front end of which is turned inwardly sufficiently to prevent disengagement of the chain when the latter is placed under a longitudinal forward stress in use, said wrench having a recess to receive the chain link when the pintles are entering into engagement with said lock.

5. In a chain wrench, the combination of a handle or shank, two jaws arranged on op-

posite sides of said handle, a chain pivoted between such jaws, said chain having locking pintles on each side thereof, and a pair of locking faces on the inner sides of said jaws
 5 adapted to engage the pintles of the chain, said locking faces comprising hook-like members opening toward the front end of the wrench and turned inwardly sufficiently to prevent disengagement of the chain when the latter is placed under a longitudinal forward
 10 stress in use.

6. In a chain wrench, the combination of a handle or shank, and two jaws arranged on opposite sides of said handle, each of said
 15 jaws having a groove adapted to receive such handle, said groove being of such depth that it does not extend into the metal beyond the plane of the inner side of the jaw, a chain centrally pivoted between such jaws, said
 20 handle terminating at the rear of the pivot pin of said chain, and a rivet passing through said jaws and handle.

7. In a chain wrench, the combination of a handle or shank, two jaws arranged on opposite sides of said handle, and a chain centrally pivoted between such jaws, said handle terminating at the rear of the pivot of such chain whereby slotting of the handle is avoided.

8. In a chain wrench, the combination of
 30 a handle or shank, and two jaws arranged on opposite sides of said handle, a chain, and means for pivoting such chain comprising a pivot pin having an eye to which said chain is attached extending from one side thereof, said eye being arranged wholly on one side
 35 of said pin, whereby the handle may be extended close to the latter.

9. In a chain wrench, the combination of a handle or shank, and two jaws arranged on
 40 opposite sides of said handle, each of said jaws having a groove adapted to receive such handle, said groove being of such depth that it does not extend into the metal beyond the

plane of the inner side of the jaw, and a chain pivoted between such jaws, said handle terminating at the rear of the pivot of such chain, whereby slotting of the handle is
 45 avoided.

10. In a chain wrench, the combination of a handle or shank, and two jaws arranged on
 50 opposite sides of said handle, each of said jaws having a groove adapted to receive such handle, said groove being of such depth that it does not extend into the metal beyond the plane of the inner side of the jaws, a chain, and a pivot for said chain, said jaws being formed with recesses in which the ends of
 55 said pivot are mounted.

11. In a chain wrench, the combination of a handle or shank, and two jaws arranged on
 60 opposite sides of said handle, each of said jaws having a groove adapted to receive such handle, said groove being of such depth that it does not extend into the metal beyond the plane of the inner side of the jaws, a chain, and a pivot for said chain, said jaws being formed with recesses in which the ends of
 65 said pivot are mounted, and said handle terminating at the rear of said pivot.

12. In a chain wrench the combination of
 70 a handle or shank, two jaws arranged on opposite sides of said handle, and a chain pivoted between such jaws, said jaws being formed with sockets adapted to receive the pivot of such chain, such sockets being of
 75 less depth than the thickness of the jaws so that the pivot is held against endwise movements.

In witness whereof, I have hereunto signed my name in the presence of two subscribing
 80 witnesses.

GEORGE AMBORN.
